UNITED STATES PATENT OFFICE.

D. R. WARFIELD, OF MUSCATINE, IOWA.

IMPROVEMENT IN GATES.

Specification forming part of Letters Patent No. 41,951, dated March 15, 1864; antedated March 9, 1864.

To all whom it may concern:

Be it known that I, D. R. WARFIELD, of Muscatine, in the county of Muscatine and State of Iowa, have invented a new and useful Improvement in Gates or the Means Employed for Opening and Closing the Same; and I do hereby declare that the following is a full, clear, and exact description of the same, reference being had to the accompanying drawings, making a part of this specification, in which—

Figure 1 is a side sectional view of my invention, taken in the line xx ; Fig. 2; Fig. 2, an end view of the same, one of the levers being in section.

Similar letters of reference indicate corresponding parts in both the figures.

This invention relates to a new and improved means for opening and closing gates to enable a person on horseback or in a vehicle to open or close the gate without dismounting from the horse or getting out of the vehicle.

The invention consists in suspending the gate on an angular pivoted bar placed in a suitable framing and arranged with a catch or fastening and levers, as hereinafter fully shown and described.

To enable others skilled in the art to fully understand and construct my invention, I will proceed to describe it.

A represents a framing, which is comprised of two upright posts, a a' , and two central posts, b . The upper ends of the posts a a' are connected by two parallel horizontal bars, c c , the centers of which are supported by posts b .

B is a fence, which is permanently attached to the post a and to one of the central posts b , and closes one-half the space between the two posts a a' —that is to say, the space between the post a and the posts b , as shown in Fig. 1.

C is a bar which is secured centrally between the two horizontal bars c c by a pivot, d . This bar C is of angular form, being inclined upward at each side of the pivot d , as shown clearly in Fig. 1.

D represents the gate, which may be made to correspond with the fence B. This gate has its posts e e extending upward a trifle above the bar C, the latter passing through mortises f f in the upper ends of the posts e e , the posts being connected above the bar C by a cross-bar, g , in which two rollers, h h , are fitted, said rollers working on a way, i , attached to the upper surface of C.

The gate D is thus suspended on the bar C, and the former is sufficiently wide to cover the open space between the post a' and the posts b .

The bar C is allowed to tilt or work freely on its pivot d , and it has a weight, E, attached to it at one end, which weight has a tendency to keep the part of the bar C directly over the space between the posts a' and b down in a horizontal position or a trifle below that position, as shown in red in Fig. 1. The bar C, when tilted so as to assume a position opposite to that above specified, as shown in black, Fig. 1, is retained by a catch, F, which is composed of a bar, j , the lower end being secured by a pin or pivot, k , to the outer side of the post a' , and its upper end passing up through a mortise, l , in the end of bar C, which projects through a mortise, m , in the upper end of the post a' , the bar j being provided with a shoulder, n , on which the bar C rests. The bar C is raised by means of levers G G, which are attached by fulcrum-pins o o to a framing, H, connected to post a' . These levers project from opposite sides of the bar C, so that the latter can be raised from either side of the gate, and the inner ends of these levers are fitted in a loop, p , at the under side of the bar C. In order to disengage the catch F to allow the loaded end of the bar C to fall, two small levers, q q , are secured in post a' at the bottom of the mortise m . These levers are both connected at one end to the bar j by a ring, r , and said levers at their opposite ends have each a cord, s , attached to them, and these cords pass through guides t at the under sides of the levers G G, and project down from said levers near their outer ends, as shown clearly in Fig. 2. A spring, u , which is attached to the outer side of the post a' , bears against the bar j and has a tendency to keep the shoulder n of the latter under the bar C at the front edge of the mortise l therein.

From the above description it will be seen that when the loaded end of the bar C is elevated and retained in that position by the catch F the gate D will be in an open state in consequence of the part of the bar C over the space between the posts a' b being inclined and causing the gate to descend by its own gravity upon the horizontal part of said bar above the fence, and when the bar C is relieved from the catch F, and the weight E tilts the bar C in the opposite direction, the gate will run down the

inclined part of the bar upon the horizontal part and be in a closed state, as shown in red in Fig. 1.

The levers G G are sufficiently high to be within convenient reaching distance of the rider or driver. The bar *j* of the catch or fastening is drawn back so as to release the bar C by pulling either of the cords *s*, the latter actuating the levers *q q*, and the latter the bar *j*.

The gate D is provided with a catch, *a^x*, at each end, which engage with pins *b^x* to prevent the gate from casually moving when in either an open or closed state. These catches are raised from the pins *b^x* by the tilting of

the bar C, so that the gate will be free to move as said bar is tilted.

I do not claim, broadly, the angular tilting bar C with the gate D suspended upon it, for that has been previously used; but

I do claim—

The bar C with the weight E attached, in combination with the catch F, levers G G, cords *s*, and levers *q q*, all arranged substantially as and for the purpose set forth.

D. R. WARFIELD.
